SWEeper FOR PARKING LOTS

Roy C. Rush, 6129 NE. Skidmore St.,
Portland, Oreg. 97218

Filed Oct. 16, 1967, Ser. No. 9,010

Term of patent 14 years

(Cl. D49—9.1)

FIG. 1

FIG. 2

FIG. 3

FIG. 4

FIG. 5

FIG. 1 is a side elevational view showing my new design for a sweeper for parking lots;

FIG. 2 is a side elevational view thereof from the side opposite that shown in FIG. 1;

FIG. 3 is a top plan view thereof;

FIG. 4 is a front elevational view thereof; and

FIG. 5 is a rear elevational view thereof.

I claim:

The ornamental design for a sweeper for parking lots, as shown.
